OPENER

Alexander M. Alexandrescu, Cleveland, Ohio

Application March 15, 1946, Serial No. 654,675

2 Claims. (Cl. 30—16)

1

This invention relates to openers such as may be used in households, restaurants or other establishments for opening cans, jars and bottles.

It is an object of the invention to provide a convenient and versatile opener which may be used for opening round or rectangular tin cans, for piercing small or relatively large holes in tin cans containing fluid, for lifting lids of cans or jars of the types which are held in place by friction or by vacuum, and for removing bottle caps.

Another object of the invention is to provide devices, embodying certain features of a combination opening device, for specialized opening operations.

Another object of the invention is to provide openers of the type which are forced into a can with structure for guiding the blade.

Another object of the invention is to provide openers of the type which are forced into a can with structure for limiting the depth of insertion of the blade.

Another object of the invention is to provide openers of the type which are forced into a can with structure for guarding the blade, both to protect the blade and to protect persons against accidental contact therewith.

Another object of the invention is to provide a can opener of the type in which a blade is rotated about a fulcrum at the center of the can top which automatically guides the cutting blade in a path adjacent the margin of the can lid.

A further object of the invention is to provide an opening device for cans containing fluid which is adapted to pierce a hole immediately adjacent the side of the can.

A further object of the invention is to provide openers which are especially adapted to economical manufacture.

Other objects and advantages more or less ancillary to the foregoing, and the manner in which all the various objects are realized, will appear in the following description, which, considered in connection with the accompanying drawings, sets forth the preferred embodiment of the invention.

Referring to the drawings:

Fig. 1 is a side view of one form of combination opening device embodying the principles of the invention;

Fig. 2 is a partial front view of the same form;

Fig. 3 is a partial rear view of the same form;

Fig. 4 is a detailed view of one part of the opener shown in Fig. 1;

Fig. 5 is a partial view illustrating a modification of the form of Fig. 1;

2

Fig. 6 illustrates the manner in which the cutting blade of the form of Fig. 1 is guided into engagement with a can which is being opened;

Fig. 7 is a front view of a modified form of opener;

Fig. 8 is an end view of the opener shown in Fig. 7;

Fig. 9 is a front view of a simplified form of opener;

Fig. 10 is a side view of the opener shown in Fig. 9;

Fig. 11 is a front view of a form of opener specially adapted for opening cans containing fluid;

15 Fig. 12 is a side view of the same;

Fig. 13 is a view of a modified form of opening device for beverage cans and bottles;

Fig. 14 is another view of the same;

20 Fig. 15 is a view of a simplified form of opener especially adapted for removing jar and can lids.

The combination opening device shown in Figs. 1-4 comprises a handle 20 into which is forced a shank 21. Disposed on one side of the shank is the combination blade member 22, formed with 25 a cutting blade 23 on its lower surface, a hook 24, which cooperates with the shank to form a cap lifter, and a bit 25 extending from one side which is particularly adapted for prying off jar lids and the like. The shapes of the blade 23 and the bit 25 which have been found to give most effective operation will be described in connection with other forms of the opener.

A member 26 is mounted on the other side of the shank from the blade member 22, members 35 23 and 22 being secured to the shank by rivets 27. At its lower end, the member 26 constitutes a piercing blade for cans, having a sharp terminal portion 29 of small cross-sectional area and a V-shaped beveled portion 30 immediately above the point 29. When it is desired to form a small hole in a can, as for the admission of air, the point 29 may be forced into the can by a small force exerted on the handle 20, and penetration of the point 29 will be stopped by the engagement of the blade 30 with the surface of the can. In case it should be desired to produce a larger opening, a greater force on the handle 20 will force the blade 30 into the can, producing a relatively large opening.

40 The upper end of member 23 constitutes a pintle 31 formed by pointing and recurring the end of the member 26. The pintle 31 comprises a portion 32 of relatively small radius and a slightly curved portion 33 directed approximately 45 ly at a 45° angle to the shank. A guided cutter

55

structure 34 (Figs. 1, 3, and 4) is slidably mounted on the shank 21. The structure 34 may be formed from a single generally cruciform blank of sheet metal, and has two opposed arms engaged around the shank for sliding engagement therewith, and another arm but at right angles to form a cutter 36 with a cutting edge 37 thereon. The fourth arm may be bent as shown to form a member 38 disposed parallel to the blade.

In one manner of use of the improved opener, an opening 40 (Fig. 6) is pierced near the center of the top of a can with the point 29. The pintle 31 is then engaged in the hole, the guide member 38 is engaged with the edge of the can, and the handle is pressed down, forcing the blade 36 into the can, pintle 31 serving as a fulcrum. By rotation of the handle in the plane of the top of the can, the blade 36 is caused to traverse the margin thereof, cutting out the lid, the guide member 38 constraining the blade to a path adjacent the rim of the can. Another feature of the improved opener is that member 26 may be made long enough so that when it is employed to open cans of a moderate or small size, member 26 overlies the edge of the can opposite blade 36, thus tending to maintain the blade 36 in the can and counteracting its obvious tendency to ride out of the can when the handle is moved in the plane of the top. The pintle 31 serves as a fulcrum for the action of the force exerted by the can on the outer portion of the member 26. It will be noted that because of the angle between the pintle and the shank, as the pintle is forced into the opening 40, the blade 36 is brought into piercing engagement with the top of the can.

As shown in Fig. 5, the advantages of the guide member 38 for maintaining the blade 36 near the edge of a can may be realized in a simpler form of the invention in which the pintle 31 is omitted. In the simplified form, the lower end of the shank 21 is reduced in section, bent at right angles to form a pintle 41, and bent again at right angles to form a piercing point 42. In this form, the point 42 may be forced into the can, and then, by lowering the handle, the pintle portion 41 may be employed as a fulcrum for the cutter 36. In this form the member 26 is, of course, omitted, and it is preferable to omit the combination blade 22.

The cutting blade 36 is, of course, adapted only for opening round cans, but the cutting blade 23 may be employed to remove the lids from cans of any shape, as will be seen by reference to the modified form of opener shown in Figs. 7 and 8 which is provided with a blade 23 of the same form as that shown in Fig. 3. In the modification of Fig. 7, however, the blade 23 is formed integral with the shank 21, as are the cap lifter 24 and the bit 25. The handle may be of the type shown in Fig. 1, or it may be formed of two pieces 45 of suitable material secured on each side of the shank by rivets 46. A V-shaped blade 47 projecting beyond the blade 23 is secured to the shank by rivets 27 and spaced from the blade 23 by a rectangular piece of thick sheet metal 48. The cutting edge 23 is disposed at an angle to the axis of the handle and shank so as to obtain a gradual shearing action of the can top as the blade is forced into it.

The blade 23 is slightly dished so that the cutting edge as seen from below (Fig. 8) is curved and tends to produce a slightly curved cut in a can top. With the blade 23 the lid of the can is removed by a series of cuts made with the blade, each cut beginning at the end of the

one previously formed. It will be noted that the blade is guided into engagement with the edge of the can top by member 26 in the form of Fig. 1, and by blade member 47 in the form of Fig. 7. The motion of the blade 23 into the can is automatically terminated by engagement of the end of the shank 21 (Fig. 1) or the lower end of spacer 48 (Fig. 8), preventing the thrust from carrying the blade deep into the can and providing for easier operation of the blade.

These advantages may, however, be secured in a somewhat different manner as illustrated by the modified form of Figs. 9 and 10, in which the only opening device shown is the cutting blade 23 mounted on shank 21 by rivets 27. The blade 23 is of the same general form as those of Figs. 3 and 7. The shank 21 is provided with an integral offset extension 50 slightly displaced from, and parallel to, the blade 23 and extending beyond the blade. The extension 50 may be used to guide the blade adjacent the edge of a can, and the shoulder where extension 50 joins the main portion of the shank 21 will serve to limit the depth of insertion of the blade. In addition, the form of guide member illustrated in Figs. 9 and 10 serves as a protective device, since the extension beyond the blade will protect the blade from accidental contact with objects which might damage it, and provide a safety device against accidental contact of a person with the blade.

This protective construction of the shank is also employed in the modified piercing device for opening cans containing fluid illustrated in Figs. 11 and 12. This form employs a blade 51 which may be regarded as an alternative for the blades 47 of Fig. 7 and 29 of Fig. 2. While each of these blades is shown in a particular modification of the device, any form of the blade may be used with any modification of the remaining portions of the device. The blade 51 is secured to the shank by rivets 27, and the side adjacent the shank is flat. The reverse side of the blade is beveled away at 52 and 53 to form cutting edges 54 and 55. In the use of this type of blade, it is plunged into the can adjacent the edge thereof, being guided by the member 50. Since the cutting blade is beveled only on the side away from the edge of the can, it has an inherent tendency to force itself toward the edge of the can and produce an opening immediately against the edge of the can.

Another manner in which the depth of insertion of a piercing blade for juice cans may be controlled is exemplified in the modified form of opening device illustrated in Figs. 13 and 14. In this form, the piercing blade 47 is formed on the end of the shank 21. Projections 56 extending from the edge of the shank limit the movement of the blade into the can. Of course, the projections 56 may be of any convenient shape such as that of bit 25. If desired, economies of manufacture may be obtained by the use of only one such projection.

In the form of Fig. 13, a handle 57 for pushing the blade into the can is formed by curving the shank back on itself. The recurved end of the shank may conveniently be disposed the proper distance from the shank to serve as a hook for bottle caps. The shank is slightly curved at 58 in the opposite direction from the curve employed in forming of the handle in order that the shank 21 will have a slight initial elevation when the device is used as a cap lifter. In this way the danger of accidental contact between the fingers

and the bottle is reduced. This same feature is exemplified in a somewhat different form in Fig. 7, in which the shank is reduced at 59 so that when the hook 24 is engaged with the underside of a cap the handle 45 slopes upward.

As has been stated, the bit 25 (Figs. 3 and 7), is provided for removing pressure sealed lids from jars or frictionally held lids such as are sometimes pressed into cans. The conformation of the bit 25 will be described in connection with Fig. 15, which illustrates a simplified form of opener designed solely for the employment of the bit 25. In this device the shank 21 and the bit 25 are stamped from a single piece of sheet metal of appropriate gauge. Bit 25 is adapted to be inserted between, for example, the lid of a jar and the shoulder usually provided on the jar immediately below the lid. The face of bit 25 is concave to fit around the cylindrical surface of a jar and provide for better engagement of its edges 60. The shank is cut away at 61 so that the concave surface of the bit is approximately in alignment with one edge of the shank 21 in order to decrease the offset of the shank, and diminish the tendency for the device to rotate about an axis through the forward face of the bit when it is employed to pry up a lid.

Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

I claim:

1. A can opener comprising a handle, a shank extending from said handle, and a blade extending from said shank, said blade having a single sharp cutting edge which is curved and concave,

the chord of said curved edge forming an acute angle with the axis of said shank to form a blade that progressively cuts a slot in a can in response to axial force applied to said handle and shank, said curved edge being substantially bisected by the medial axis of said shank.

5 2. A can opener comprising a handle, a shank extending from said handle, and a blade extending from said shank, said blade having a single sharp cutting edge which is curved and concave, the chord of the curve of said edge forming an acute angle with the axis of said shank to form a blade that progressively cuts a slot in a can in response to axial force applied to said handle and shank, said blade being relatively wide and being slightly curved about an axis generally parallel to that of said shank to accommodate a rounded can, said curved edge being substantially bisected by the medial axis of said shank.
